**APPARATUS FOR AUTOMATICALLY REMOVING
LINT FROM ABOVE AND BELOW THE WARP
OF TEXTILE LOOMS**

Carroll deV. Miller, Rocky River, and Francis N. Becker, Cleveland, Ohio, assignors to The American Monorail Company, Cleveland, Ohio, a corporation of Ohio

Application December 27, 1950, Serial No. 202,856

8 Claims. (Cl. 15—312)

This invention relates to the art of cleaning textile machinery and is particularly concerned with new apparatus for freeing a loom of lint and maintaining it in substantially lint-free condition.

Heretofore, there has been no automatic apparatus for cleaning looms so far as we know. The practice has always been for an operator to use compressed air to blow accumulated lint off the various parts of the loom from time to time when the accumulation became so large that it interfered with the weaving operation. Although it has long been recognized that it would be highly desirable to have apparatus which would automatically free a loom of lint and keep it in clean condition, no one has heretofore devised any apparatus which was satisfactory for that purpose.

The present invention provides apparatus which is automatic in operation and is capable of cleaning a plurality of looms and maintaining them in substantially lint-free condition.

The present invention will be better understood by those skilled in the art from the following description taken with the drawings which accompany this specification and in which:

Fig. 1 is a side elevational view of one embodiment of the present invention shown in its association with a loom;

Fig. 2 is an end elevational view of the apparatus and loom of Fig. 1;

Fig. 3 is an enlarged side elevational view of the form of the invention shown in Fig. 1;

Fig. 4 is an end elevational view of the apparatus of Fig. 3;

Fig. 5 is a top plan view taken on line 5—5 of Fig. 3 with parts broken away;

Fig. 6 is a bottom plan view of the apparatus of Fig. 3 with parts broken away;

Fig. 7 is a fragmentary, side view, partly in section, of a modified form of fan housing and nozzle actuating means;

Fig. 8 is an end view, with parts broken away, of the apparatus of Fig. 7;

Fig. 9 is a fragmentary top plan view, partly in section, of the apparatus of Fig. 7;

Fig. 10 is a side elevational view of a modified form of apparatus embodying the invention;

Fig. 11 is a top plan view, with parts broken away, of the nozzle shifting apparatus of Fig. 10; and

Fig. 12 is an end elevational view of the apparatus of Fig. 10.

The apparatus shown in Figs. 1 to 6 includes a monorail track 1 suspended over a loom 2 of a row of looms and serving as a runway for trolleys 3 which support a carriage 4 below the track.

Two motors 5 are attached to the carriage 4 on the under side thereof and the extended rotor shafts 6 of these motors project in opposite directions from the remote ends of the motors. Each shaft 6 has a centrifugal fan 7 affixed to its end. The carriage, motors and fans are positioned above the arch G of the loom and move length-

2

wise of the loom harness F. Each centrifugal fan is enclosed in a housing 8 which has an axial air intake 9 and a peripheral nozzle outlet 10 disposed to direct air downwardly beside the harness. Each housing 8 has plate 11 on its side opposite the intake 9 and this plate is attached to a cylinder 12 which carries bearings 13 supported on shafts 6. Thus, each housing may be rotated about the rotor shaft 6 so as to change the direction of streams of air issuing from outlets 10.

The motors 5 are energized by current brought to them through conductors 15 connected to collectors 16 which engage electrically energized bus bars 17 above track 1.

Each cylinder 12 has threaded post 20 extending radially outward therefrom at substantially a right angle to the axis of the rotor shaft 6. Links 21 disposed at substantially right angles to the axes of the rotor shafts 6 are adjustably connected at one end to posts 20 and at the other end to plates 22 which are pivotally supported on a pin 23 depending from the carriage 4. A rod 25 disposed at substantially right angles to link 21 is slidably mounted in bearings 26 on the under side of carriage 4 and is connected at its opposite ends to plates 22. Stops 27 attached to rod 25 serve to engage the adjacent bearing 26 alternately to limit the extent of endwise movement of rod 25. Collars 28 are connected to shaft 25 in spaced relation and between them is mounted a sleeve 29 which is slidable on the rod 25 and is disposed between the adjacent ends of two springs 30 the remote ends of which abut against collars 28. Sleeve 29 has an upwardly projecting pin 31 which is disposed in the bifurcated end of arm 35 which is mounted on pivot 36 and is connected to a bar 37 disposed at substantially right angles thereto. The ends of bar 37 are tapered as indicated at 38 to engage with lugs 39 depending from plates 49 which are pivotally connected to carriage 4 by pivots 41 and are connected at their free ends by spring 42.

As is shown in Fig. 5, pivot 36 extends up through carriage 4 and is keyed to a lever 45 which is pivotally connected at its ends to the ends of links 46. These links are connected intermediate their ends by a spring 47 and are also connected by two links 48 pivoted thereto and to each other. One of these links 48 has a lost motion slot 49 in which a pin connected to the other link slides. The slot carrying link is pivotally connected at its free end to pusher bar 55 by pin 51. The free ends of links 46 are beveled as indicated at 56 to engage with the pusher bar 55.

Pusher bar 55 is connected to the end of pusher rod 57 which is slidably mounted in bearings 58 on top of carriage 4 and at its outer end carries a roller 59 to engage with an abutment (not shown) fixed along the track 1.

The operation of the apparatus of Figs. 1 to 6, if not entirely clear from the foregoing detailed description of the various parts thereof and their relation to one another, will be fully understood from the following brief description. When the carriage 4 is moving along track 1 and current is being supplied to motors 5 with resultant rotation of centrifugal fans 7, streams of air will be blown through outlets 10 of each of the housings 8. Since the housings are initially set so that the streams of air are directed downwardly at different angles to the vertical, these streams will trace different, separate paths across the loom 2 on opposite sides of the harness F as the carriage moves over the loom at substantially right angles to the warp, i. e., parallel to the warp beam B and cloth roll C. When the carriage next approaches the loom, roller 59 will engage the fixed abutment and thereby will move pusher rod 57 endwise and press pusher bar 55 against the beveled end 56 of one of the links 46. The pressure of bar 55 on link 46 turns lever 45 about the center line of pin 36 and this turning move-

ment shifts the other link 46 and links 48 and 49 and moves the pivotal connection between links 48 and 49 to the other side of the center line of pusher rod 57. Simultaneously the link 46 is moved out of engagement with pusher bar 45 and the other link 46 is brought into engagement therewith. Since arm 35 and bar 37 are keyed to pivot 36, these parts will shift simultaneously with lever 45, this shifting movement being resisted by spring 42 which presses lugs 39 against the tapered ends 38 of bar 37. The turning movement of arm 35 about the center line of pivot 36 moves sleeve 29 toward the right as seen in Fig. 6, thereby compressing the right-hand spring 30 and urging rod 25 endwise toward the right in that figure.

As rod 25 moves endwise, it rotates plates 22 about their pivot pins 23 and these plates move links 21 endwise and thereby rotate cylinders 12 about motor shafts 6 with the result that each of the housings 8 will be shifted or rotated through a short angular distance about shaft 6 and the directions of the streams of air issuing from outlets 10 will be changed. In other words, when the carriage moves across a given loom the streams of air will blow downwardly from a level above the arch of the loom and on opposite sides of the harness F in directions to trace two different, separate paths across the loom and, on the next passage of the carriage over the loom, the housings will be shifted so that the air streams will then trace different, separate paths across the loom. On the next trip over the loom the streams will be shifted back to the original paths.

Thus, two streams of air may each be caused to trace two paths across the loom, each path being equal to about $\frac{1}{4}$ of the distance from the warp beam to the edge of the cloth over the cloth roll and in the next passage of the carriage over the loom, the streams of air may be shifted so as to trace two other paths each equal in width to the width of the first pair of paths and covering the half of the loom not covered by the first two paths. Conveniently, in the first passage of the carriage over the loom one stream D may extend from the warp beam about half way to the harness F and the other stream E may extend from the harness to beyond the path of the shuttle, that is, about half way to the edge of the cloth above the cloth roll. On the next passage of the carriage over the loom the first stream of air may be shifted to the position D' so that it will extend from the harness F about half way to the warp beam and the other stream E' will extend from the edge of the cloth over the cloth roll beyond the path of the shuttle and about half way to the harness.

Figs. 7, 8 and 9 show a modified form of housing and nozzle shifting means. In these figures the apparatus is generally the same as that shown in Figs. 1 to 6, the principal difference being in the details of construction of the housing and its shifting means.

The link 21a is connected to a threaded post 20a which is fixed at its ends in a bracket 60. The motor 5a has a rotor shaft 6a which projects only a short distance beyond the motor housing as compared with motor shaft 6 of Fig. 2. A disk 61 carries a bearing 61a which is mounted on shaft 6a so that the disk may remain fixed while the shaft rotates. Posts 62 are affixed to the motor housing and to disk 61 to support and prevent the plate from rotating. At its outer periphery disk 61 is surrounded by two rings 63, each substantially half as thick as the disk 61. Housing 8a, which is substantially like housing 8 of Figs. 1 to 6, inclusive, is secured to the outer periphery of these rings 63. These rings are connected together (by means not shown) and are attached to bracket 60 as by cap screws 64. The outer periphery of disk 61 and the inner peripheries of rings 63 are cut away to provide a runway for ball bearings 65. Rods 21a may be actuated endwise by means substantially like the means shown in Figs. 1 to 4 and including cam 22, rod 25 and rod 57.

When the housing shifting mechanism including rod 25, cam 22 and link 21 are shifted as described above in connection with Figs. 1 to 6, rings 63 are moved rotatively on disk 61 and shift housing 8a rotatably on that disk so as to trace paths across the loom as described in connection with apparatus of Figs. 1 to 6.

It will be understood that the extent of shifting of the housings 8 and 8a depends on the location of the link 21 or 21a on posts 20 or 20a, respectively. When either of these rods is located near the outer end of its post the angle through which the housing is shifted is at its maximum and when the connection of either rod is near the inner end of its post the angularity of the shifting of the housing is at its minimum. Thus, by adjusting the position of the connection of the links on the posts, any desired angularity of shifting of the streams of air may be obtained within the limits permitted by the adjustment of the rods on the posts.

If, however, it is desired to employ only one blower 20 instead of two, one of the two units comprising one motor and blower and the linkage connections associated therewith may be omitted. In this case provision should be made to shift the remaining housing 8 into four different positions so as to trace four paths across the loom such as are traced by the two above described blowers. To that end, other shifting mechanism may be substituted for the mechanism hereinabove described, one form of mechanism suitable for this purpose being shown in Figs. 10 to 12, inclusive.

In the modification shown in Figs. 10, 11 and 12, a single motor 5b is supported beneath a carriage 4a which, in turn, is supported by trolleys 3 running on track 1. The horizontally extended rotor shaft 6b carries a centrifugal fan 7 at its outer end and projects through a disk 61b which is supported by struts 62b projecting from the motor housing. This disk carries two rings 63b on its periphery, the rings being freely rotatable on the disk by reason of intervening roller bearings 65b. These rings 63b are connected to each other and to fan housing 8a which surrounds them by means not shown.

The outer ring 63b has an outstanding post 73 to which is attached one end of rod 21a. A pivot post 74 extending downwardly from carriage 4a supports a cam 75. The other end of rod 21a is connected to this cam, as is also one end of rod 25a. The other end of rod 25a is pivotally connected to cam 22a which is supported for rotation with shaft 36a which extends up through carriage 4a. Above carriage 4a, shaft 36a has keyed thereto a plate unit 76 consisting of two rectangular plates spaced apart from each other a short distance and provided with a pair of aligned notches 77 on each of the four sides. Rod 57a carries a roller 59 at one end and slides in bearings 58a attached to carriage 4a. A collar 77a keyed to rod 57a and a spring 78, which is compressed between that collar and one bearing 58a, serves to move rod 57a in a direction opposite to that caused by the engagement of roller 59 with a fixed abutment and thus restores the rod substantially to the position shown in Fig. 11 after actuation by the engagement of roller 57 with the abutment. At its end opposite roller 59, rod 57a has a block 79 which pivotally carries a finger 80 of a size to enter the aligned pair of notches 77 in unit 76. This finger is urged by a spring (not shown) into a position at right angles to the axis of rod 57a, i. e., to the position shown in Fig. 11 and is provided with stop means to limit its motion in the direction in which it is urged by the spring. In other words, the finger 80 may move into a position parallel to the axis of rod 57a by overcoming the resistance of the spring when the finger engages an abutment during the return stroke of rod 57a but when the abutment no longer engages the finger the spring takes over and restores the finger to a position at right angles to the rod.

A rod 81 mounted to slide endwise in bearings 82 on carriage 4a and parallel to rod 57a is provided with a bifurcated end 83. The extremities of this end are fitted

with rollers 84 which engage unit 76. Spring 85 serves to urge rod 81 toward unit 76.

When rollers 84 engage adjacent sides of unit 76, i. e., straddle a corner thereof, the unit will be fixed in position and as a result the fan housing 8a will be fixed in position. When roller 59 engages an abutment along the track 1 and rod 57a is thereby moved endwise, finger 80 will be pressed against unit 76 and will rotate that unit. As the unit rotates, the finger 80 moves into an aligned pair of slots 77, rotates the unit 90° and moves out of the slots. When roller 59 moves out of engagement with the abutment along the track, spring 78 takes over and urges rod 57a endwise in the opposite direction and this movement of the rod brings finger 80 into contact with unit 77 which serves as an abutment to rotate the finger against the spring attached thereto. When the free end of the finger passes the adjacent corner of unit 76, the spring serves to restore the finger to its normal position as shown in Fig. 11.

The 90° rotation of unit 76 results in shifting the outlet 10a of housing 8a from one of the four positions to an adjacent position, all as indicated in Fig. 12. Thus, with the stream of air issuing from nozzle 10a being of sufficient size to cover approximately 25% of the width of the loom and with the use of the just described mechanism, the stream of air may be made to trace four separate paths across the loom in as many passages thereover. It will be understood that a single fan device such as is shown by this modification should be used to clean only about half as many looms as the double fan device of Figs. 1 to 9, inclusive.

It will be understood that the modified form of apparatus shown in Figs. 10 to 12, inclusive, operates in substantially the same manner as has been described above in connection with Figs. 1 to 9, inclusive.

The volume and velocity of air which is delivered to the loom are critical. If the volume or velocity is too great the air will actuate the stop motions and shut down the loom; and, on the warp side of the loom, will blow down through the warp and onto the floor where it will stir up lint and blow it toward other machines; and on the cloth side of the loom there will be much more air than the operators desire. We have found that when the air stream at the cloth level of the loom has a lineal speed of between about 2,000 and about 2,800 feet per minute and a volume of between about 800 and about 1,200 cubic feet per minute, the loom will be effectively and satisfactorily cleaned and will continue to operate properly. Air in smaller volume or at lower velocity, or both, will be ineffective in cleaning the parts of the loom beneath the warp while air in greater amounts or at greater velocity, or both, will actuate the stop motions and create undesired conditions. In general, the velocity may be the same for both the warp and cloth sides of the loom but the volume should be a little less for the cloth side than for the warp side. The foregoing limits include these variations.

The volume and velocity of air at the cloth level may be varied within the foregoing limits in various ways. If a given blower installation delivers too great a volume of air, the volume may be decreased by fitting a ring into the intake opening, as opening 9 of Fig. 4, the radial width of this ring being such as to reduce the air taken in sufficiently to bring the volume of air delivered through the outlet opening down to the desired amount. In other words, by varying the size of the intake with what might be called adapter rings, the volume of air delivered at the cloth level may be varied as desired.

If it is desired to vary the velocity of the air at the cloth level, this may be done by varying the distance between the outlet nozzle of the fan housing and the cloth level of the loom. If the velocity at the cloth level is to be increased with a given blower installation, the blower may be lowered closer to the arch of the loom or the same effect may be obtained by providing the nozzle with an

extension which releases the air closer to the arch of the loom. Similarly, if the velocity at the cloth level is to be decreased, the blower installation may be moved farther away from the arch of the loom or the outlet from the fan housing may be effectively raised by taking away removable extensions thereof.

Having thus described the present invention so that others skilled in the art may be able to understand and practice the same, we state that what we desire to secure by Letters Patent is defined in what is claimed.

What is claimed is:

1. Apparatus for cleaning textile looms comprising a frame to travel repeatedly over a row of looms, a motor carried by said frame and having a substantially horizontal rotor shaft, a centrifugal fan fixed to said shaft, a substantially vertical casing around said fan and having a substantially vertical nozzle opening downwardly from the casing on one side of the harnesses of the looms, said fan when rotating and traveling over the looms serving to discharge air through the nozzle and down onto the warp of the looms in a stream substantially less in width at the warp level than the length of the warp from the warp roll to the harness and capable of passing between the warp strands and removing lint from parts of the looms below the warp level in the path of the stream but incapable of actuating the stop motions of the looms, and means operatively associated with said nozzle for automatically and at regular intervals reciprocating said stream about a horizontal axis substantially parallel to the line of travel of the frame to move the stream substantially normal to the line of travel of the frame in a manner that during repeated movements of the blower over the looms the air stream is directed in varying directions against each loom and in a manner to pass said stream between substantially all the warp strands on the looms and between substantially all the different portions of those strands from the warp roll to the harness of each loom during repeated movements of the frame over the looms.

2. Apparatus for cleaning textile looms comprising a frame to travel repeatedly over a row of looms, a motor carried by said frame, a centrifugal fan rotatable by said motor about a substantially horizontal axis, a substantially vertical casing around said fan and having a substantially vertical nozzle opening downwardly from the casing on the warp roll side of the harnesses of the looms, said fan when rotating and traveling over the looms serving to discharge air through the nozzle and down onto the warp of the looms in a stream substantially less in width at the warp level than the length of the warp from the warp roll to the harness and capable of passing between the warp strands and removing lint from parts of the looms below the warp level in the path of the stream but incapable of actuating the stop motions of the looms, and means operatively associated with said nozzle for automatically and at regular intervals reciprocating said stream about a horizontal axis substantially parallel to the line of travel of the frame to move the stream substantially normal to the line of travel of the frame in a manner that during repeated movements of the blower over the looms the air stream is directed in varying directions against each loom and in a manner to pass said stream between substantially all the warp strands on the looms and between substantially all the different portions of those strands from the warp roll to the harness of each loom during repeated movements of the frame over the looms.

3. Apparatus for cleaning textile looms comprising a frame to travel repeatedly over a row of looms, a motor carried by said frame, a centrifugal fan rotatable by said motor about a substantially horizontal axis, a substantially vertical casing around said fan and having a substantially vertical nozzle opening downwardly from the casing on the cloth roll side of the harnesses of the looms, said fan when rotating and traveling over the looms serv-

ing to discharge air through the nozzle and down onto the warp of the looms in a stream substantially less in width at the warp level than the length of the warp from the cloth to the harness and capable of passing between the warp strands and removing lint from parts of the looms below the warp level in the path of the stream but incapable of actuating the stop motions of the looms, and means operatively associated with said nozzle for automatically and at regular intervals reciprocating said stream about a horizontal axis substantially parallel to the line of travel of the frame to move the stream substantially normal to the line of travel of the frame in a manner that during repeated movements of the blower over the looms the air stream is directed in varying directions against each loom and in a manner to pass said stream between substantially all the warp strands on the looms and between substantially all the different portions of those strands from the harness to the cloth of each loom during repeated movements of the frame over the looms.

4. Apparatus for cleaning textile looms comprising a frame to travel repeatedly over a row of looms, motor means carried by said frame, centrifugal fans rotatable by said motor means about substantially horizontal axes, substantially vertical casings around said fans and having substantially vertical nozzles opening downwardly from the casings on opposite sides of the harnesses of the looms, said fans when rotating and traveling over the looms serving to discharge air through the nozzles and down onto the warp of the loom in streams substantially less in width at the warp level than the length of the warp from the cloth to the harness and capable of passing between the warp strands and removing lint from parts of the looms below the warp level in the paths of the streams but incapable of actuating the stop motions of the looms and means operatively associated with said nozzles for automatically and at regular intervals oscillating said streams about horizontal axes substantially parallel to the line of travel of the frame to move the streams substantially normal to the line of travel of the frame in a manner that during repeated movements of the blower over the looms the air streams are directed in varying directions against each loom and in a manner to pass said streams between substantially all the warp strands on the looms and between substantially all the different portions of those strands from the harness to the warp roll and to the cloth of each loom during repeated movements of the frame over the looms.

5. Apparatus for cleaning textile looms comprising a frame to travel repeatedly over a row of looms, a motor carried by said frame and having a substantially horizontal rotor shaft disposed with its axis substantially parallel to the line of travel of the frame, a centrifugal fan affixed to said shaft, a substantially vertical casing around said fan, oscillatable about the axis of said shaft and having a nozzle disposed to direct air downwardly from the casing on one side of the harnesses to the looms, said fan when rotating and traveling over the looms serving to discharge air through the nozzle and down onto the warp of the looms in a stream substantially less in width at the warp level than the length of the warp from the warp roll to the harness and capable of passing between the warp strands and removing lint from parts of the looms below the warp level in the path of the stream but incapable of actuating the stop motions of the looms and means operatively associated with said casing for automatically and at regular intervals oscillating said casing about said rotor shaft axis to move the stream substantially normal to the line of travel of the frame in a manner that during repeated movements of the blower over the looms the air stream is directed in varying directions against each loom and in a manner to pass said stream between substantially all the warp strands on the looms and between substantially all the different portions of those strands from the warp

roll to the harness of each loom during repeated movements of the frame over the looms.

6. Apparatus for cleaning textile looms comprising a frame to travel repeatedly over a row of looms, a motor carried by said frame, a centrifugal fan rotatable by said motor about a substantially horizontal axis, a substantially vertical casing around said fan and having a nozzle disposed to direct air downwardly from the casing on one side of the harnesses of the looms, said fan when rotating and traveling over the looms serving to discharge air through the nozzle and down onto the warp of the looms in a stream substantially less in width at the warp level than the length of the warp from the warp roll to the harness and capable of passing between the warp strands and removing lint from parts of the looms below the warp level in the path of the stream but incapable of actuating the stop motions of the looms, and means operatively associated with said nozzle for automatically and at regular intervals oscillating said nozzle about an axis substantially parallel to the line of travel of the frame to move the stream substantially normal to the line of travel of the frame in a manner that during repeated movements of the blower over the looms the air stream is directed in varying directions against each loom and in a manner to pass said stream between substantially all the warp strands on the looms and between substantially all the different portions of those strands from the warp roll to the harness of each loom during repeated movements of the frame over the looms.

7. A traveling cleaner mounted for travel above and transversely of the warp of a plurality of textile looms which comprises a frame, two casings each having a depending nozzle, two motors supported by and fixed against movement relative to the frame, two centrifugal fans one in each casing and fixed to the rotor shafts of said motors for rotation by the latter, said shafts extending substantially parallel to the line of travel of the cleaner and spaced apart therealong in approximate alignment with the fans on the remote ends of the shafts, said fans acting during the travel of the cleaner to draw air from the room into the casings and to discharge the air through the nozzles in streams on opposite sides of the loom harness and extending lengthwise of the warp and having high velocity, low volume and restricted areas at the warp level and being capable of removing lint from above the warp and of blowing through the warp and removing lint from loom parts below the warp but incapable of actuating the stop motions of the looms, and means connected to the nozzles and acting during the travel of the cleaner automatically and simultaneously to cause said streams of air to move about axes substantially parallel to the line of travel of said cleaner and lengthwise of the warp.

8. A traveling cleaner mounted for travel above and transversely of the warp at a plurality of textile looms which comprises a frame, two casings each having a depending nozzle, two motors supported by and fixed against movement relative to the frame, each motor having a rotor shaft extending substantially parallel to the line of travel of said cleaner, said casings being rotatable about the longitudinal axes of said rotor shafts, two centrifugal fans one in each casing and fixed to the rotor shafts of said motors for rotation by the latter, said fans acting during the travel of the cleaner to draw air from the room into the casings and to discharge the air from the casings and to discharge the air through the nozzles down upon the warp of the looms in streams extending lengthwise of the warp on opposite sides of the loom harness and having high velocity, low volume and restricted areas at the warp level and being capable of removing lint from above the warp and of blowing through the warp and removing lint from loom parts below the warp but incapable of actuating the stop motions of the looms, and means connected to the nozzles and acting during the travel of the cleaner automatically and simul-

taneously to rotate the casings and thereby to cause said streams of air to move lengthwise of the warp.
